UNITED STATES PATENT OFFICE.

HENRY F. PAULEY, OF SACRAMENTO, CALIFORNIA.

BOLT.

1,142,618.

Specification of Letters Patent.

Patented June 8, 1915.

Application filed May 15, 1914. Serial No. 838,827.

To all whom it may concern:

Be it known that I, HENRY F. PAULEY, a citizen of the United States, residing at Sacramento, in the county of Sacramento and 5 State of California, have invented new and useful Improvements in Bolts, of which the following is a specification.

The present invention relates to improvements in securing or connecting means for 10 a bolt or screw and is primarily adapted for employment in places where a nut cannot conveniently be arranged to connect with the bolt, the object of the invention being to provide a device of this character which 15 shall be self-propelling and obviates the liability of the loosening or withdrawal of the same, and which shall engage with and retain a bolt.

With the above recited object in view, 20 and others which will appear as the nature of the improvement is more fully understood, the improvement resides in the construction, combination and arrangement of parts set forth in the following specification and falling within the scope of the appended claims.

In the drawing: Figure 1 is a sectional view taken through a socket showing the application of my improvement, Fig. 2 is a 30 perspective view of the socket member, the fingers or prongs thereof being illustrated in their outward swinging position, Fig. 3 is a view similar to Fig. 1 but illustrating the screw engaging the fingers of prongs to 35 swing the same to engagement with the structure upon which the socket is arranged, Fig. 4 is a longitudinal sectional view through the socket taken at right angles to the prongs, and Fig. 5 is a transverse sectional view through the device illustrated in 40 Fig. 1.

Referring now to the drawing in detail, the numeral 1 designates the article to which the device is to be applied, and the inner 45 face or wall of the said article may be concealed by a surrounding structure, so that access thereto is not readily obtainable, and whereby a nut could not successfully be sustained against the said inner face to receive 50 a bolt passing through an opening therein. Also the nature of the article is such that a screw could not with efficiency supplant the employment of a nut and bolt, as for instance, the article may be of metal, or the 55 screw may be subjected to a severe strain

which it could not for any length of time withstand.

1 designates a member or plate which is provided with any number of round openings, only one being shown in the drawing and which is designated by the numeral 2, the said opening being of a size corresponding with the cross sectional diameter of a socket member 3. This socket has a closed end which is tapered, as at 4, and the same has its bore threaded, as at 5, from its opposite or outer open end. The socket adjacent its pointed or cone-shaped end 4 is provided, at diametrically opposite points, with longitudinally extending slots 6, and 65 arranged within each of these slots is a finger 7 which is pivotally secured therein, as at 8. The ends of the slot 6 adjacent the open end of the socket are beveled or inclined toward the tapered end of the said 70 socket and the fingers 7 have their ends, which engage with the said walls, inclined or beveled toward each other, so that the sharpened ends of the fingers will lie against the beveled or inclined end walls of the slots to slightly project the pointed ends of the 75 said fingers beyond the opposite sides of the slots. The fingers are of a width sufficient to contact with each other when arranged within the socket which also provides for the pointed ends being projected a slight distance beyond the sides of the 80 pocket. The socket is inserted within the opening 2, its cone-shaped end 4 being first passed to within the opening, and its outer 85 open end may be arranged flush with the outer face of the member 1. When the device is employed as a drawer pull, a flanged escutcheon plate 9 provided with a bolt 90 opening is arranged upon the outer face of the member 1, the opening in the said member 9 registering with the member 2. The knob or handle 10 may be provided with a screw member 11, or the said portion may be employed for securing the knob or handle, and this screw passes through the opening in the escutcheon plate and engages with the threads in the bore of the socket. It should be stated that the projecting sharpened portions of the fingers 7 will contact with the 95 opposite walls of the bore or opening and prevent the rotation of the socket. When the screw is rotated to draw the socket toward the escutcheon 9 and knob 10 the fingers 7, biting in the opposite walls provided 100 105 110 115

by the opening will be firmly embedded therein and so the knob and escutcheon will be effectively sustained upon the member 1.

In Fig. 3 I have illustrated the bolt or screw 11 having a shank of a length sufficient to contact with the oppositely rounded inner ends of the fingers 7, which contact will force the said fingers outwardly through the slot 6 of the socket to force the same into engagement with the walls of the opening 2'. Should the socket pass sufficiently through the article to permit of its fingers spreading outwardly against the inner face of the said article a flanged member, similar to the escutcheon 9, serving as an abutment for the head of the screw or bolt, will force the sharpened ends of the fingers tightly against the inner face of the said article, after the socket is drawn toward the flanged members, and, as a matter of fact, the said flanged member may be in the form of a drawer pull, as will be readily understood.

From the above description, taken in connection with the accompanying drawings, the simplicity of the device, as well as the advantages thereof will, it is thought, be perfectly apparent to those skilled in the

art to which such invention appertains without further detailed description.

Having thus described the invention, what I claim is:

In combination with an article having an opening, an interiorly threaded socket inserted within the opening, said socket having opposite elongated slots, the outer end walls of which being inclined, fingers pivoted within the socket and having sharpened ends, said fingers contacting with each other and with the beveled end walls of the slots to project the sharpened ends of the fingers beyond the opposite sides of the socket, a flanged escutcheon, a screw working through the escutcheon engaging with the threaded bore of the socket to force the socket toward the escutcheon and the sharpened projecting ends of the fingers in biting engagement with the opposite walls provided by the opening in the article.

In testimony whereof I affix my signature in presence of two witnesses.

HENRY F. PAULEY.
